UNITED STATES PATENT OFFICE

2,010,959

SYSTEM FOR CORRECTING SOUND RECORDS

Key J. Pomeroy, Los Angeles, Calif., assignor to
Radio Corporation of America, a corporation
of Delaware

Original application May 22, 1928, Serial No.
279,790, now Patent No. 1,828,941, dated October
27, 1931. Divided and this application September
28, 1931, Serial No. 565,571. Renewed Sep-
tember 15, 1933

9 Claims. (Cl. 179—100.3)

This invention relates generally to sound recordation and reproduction; and it may be stated as a general object of the invention to provide methods and means for compensating the 5 distortions which arise in the recordation and reproduction of sound. This case is a companion to my application entitled "System for correcting sound records", Ser. No. 279,789, filed May 22, 1928, Patent No. 1,828,940, issued Oct. 27, 1931, 10 and is directed to the general subject matter therein set forth. The present invention is within the scope of the broader claims included within said prior application. The present application is a division of my application entitled "System for correcting sound records", Ser. No. 279,790, filed May 22, 1928, Patent No. 1,828,941, Oct. 27, 1931, and comprises subject matter and claims divided from said original application.

The invention is broadly applicable to any 20 record of sound waves, but is probably most conveniently illustrated and described in connection with the photographic type of record. The particular type of photographic record with which I have chosen to illustrate the invention consists 25 of shaded band of constant density, a wavy or variable outline representing the sound character and volume. It is to be understood, however, that no limitation to that type of record is intended by such illustration.

30 In recording and reproducing sound, distortions are always introduced by reason of non-linear characteristics of the various units involved. In photographic recording, it is often true that the chief distortions are introduced in 35 the reproducing systems, and particularly by the speaking unit, the distortions of the recording system being relatively small by comparison, and the chief concern is therefore with the distortions of reproduction.

40 It may now be stated as the general object of the present invention to provide improved and simplified means for compensating these distortions of recordation and reproduction.

The general method involves the making of a 45 distortion corrected record by introducing to an original record correction distortions which are compensatory of, or have a neutralizing effect on, the distortions which are introduced by the various units of the system. In the previously mentioned case, Ser. No. 279,789, this is accomplished by what may be termed a photographic method, in which an original photographic record is made, and then reproduced as sound. The distorted sound thus obtained is photographically recorded, 50 and a negative of the original record to make a

correction record, and this correction record is finally photographically combined side by side with an original record to make the distortion corrected record. In Patent No. 1,828,941, of which the present application is a division, there is described a method which substitutes for the photographic combining of the original and distortion records, the combining of electrical sound currents representing the distortion and original records, whereby a resultant electrical current is obtained representing the differences of said record, or in other words the distortion alone. A record of this distortion current is then made upon a film and then subsequently printed side by side along with an original record, or the distortion representing record may be made directly upon a film containing the original record. In either case, the result is a distortion corrected record, or in other words an original record to which the distortion has been relatively added in a reverse sense, so that the distorting effects of the units involved in reproducing the record will result in the sound finally reproduced having the original undistorted wave form.

The method specifically claimed in application Ser. No. 279,790 involves the making of an original record, the reproduction and recording of sound from a sound current corresponding to that used in making said original record, whereby there is obtained both an original record and a record involving the distortions of reproducing and recording sound, then producing sound currents from each of said records simultaneously and combining said currents differentially so that a current representing the distortion only is obtained, recording that distortion representing current, and finally combining the record so obtained with an original record. The specific variation claimed within the present application involves a simplification in that no actual record of the sound as distorted in the reproducing and recording systems is made, the electrical current used in the other system to make said distortion record being combined at once with the original record current so as to obtain the distortion representing or correcting record in the first step.

Reference is now directed to the accompanying drawings in which:

Fig. 1 is a diagrammatic layout of a system for making the original sound record and the distortion representing or correcting record;

Fig. 2 shows an original negative photographic record;

Fig. 3 is a diagram of the electrical current used to make the original record;

Fig. 4 is a diagram of the electrical current distorted by the system;

Fig. 5 shows the current obtained by differentially combining the currents of Figs. 3 and 4;

Fig. 6 shows a photographic distortion-correction record made by recording the current of Fig. 5;

Fig. 7 shows a photographic distortion corrected record; and,

Fig. 8 shows a variational system for making the distortion corrected record in one step.

In Fig. 1 of the drawings microphone M_1 is shown connected by leads 18 and 11 to amplifier A_1 . Amplifier A_1 and other amplifiers to be mentioned may be any suitable electrical or vacuum tube amplifiers adapted to amplify audio frequency currents. The output leads 12, 13 of amplifier A_1 are connected to a glow tube G_1 , or other light varying device, before which travels the film 14. A plate having a slit S_1 is shown interposed between the glow tube and the film. A second plate having a slit S_2 is shown positioned opposite the glow tube, and beyond it is a photoelectric cell P_1 . Leads 15, 16 from the photoelectric cell P_1 connect to an amplifier A_2 , and the output leads 22, 23 of amplifier A_2 connect to a speaker H . Microphone M_1 picks up the original sound, and an electrical sound current is conducted therefrom by leads 16, 11 to amplifier A_1 , and thence, in amplified state, is conducted by leads 12, 13 to glow tube G_1 , the traveling film 14 being light affected by the glow tube to take a negative sound record N_0 of the original undistorted sound. A negative photographic record, in the terminology herein employed, is the original photographic record employed in obtaining sound. A positive record is a reversal of this negative, or in other words is the record which would be obtained by ordinary light printing from a negative record. The record N_0 actually contains distortions introduced within the recording system, but these are capable of being reduced to comparatively negligible proportions, and the distortions of recording may therefore be disregarded for the instant purpose, it being later shown, however, that the recording distortions are also compensated by the system. Light rays are also transmitted from glow tube G_1 through slit S_2 and affect the photoelectric cell P_1 , and resulting sound current from the photoelectric cell is conducted by leads 15, 16 to amplifier A_2 , the amplifier current passing to speaker H and there being reproduced as sound.

Sound reproduced by speaker H is picked up by microphone M_2 , a sound current being conducted therefrom to an amplifier A_3 . The output leads 20 and 21 of amplifier A_3 then carry an electrical current which is identical with that in the output circuit 12, 13 of amplifier A_1 except for having imposed thereon the distortions arising in the reproducing system P_1, A_2 , and H , and the recording system M_2 and A_3 . The reproducing system P_1, A_2, H must be one having characteristics identical with the one to be used in final reproduction, and the recording system M_2, A_3 , is one having characteristics identical with the original recording system M_1, A_1 , or one introducing little or no distortion.

The electrical currents in circuits 12, 13 and 20, 21 are now to be differentially combined, and for this purpose connections such as leads 60 and 61 may be made between said circuits. Circuits 12, 13 and 20, 21 are connected with such regard for polarity that their currents oppose one another, 75 the resultant current then representing their

difference, or in other words the distortion alone. Potentiometers 64 and 65 are shown connected in the circuit for the purpose of so balancing the potentials that the current components can exactly neutralize, leaving simply the differential distortion current. In balancing the circuit, I may proceed as follows: For the system of Fig. 1 there may be at least one frequency of sound current at which there will be substantially no distortion. This frequency being ascertained, it is induced in the system, and the system is then balanced, as by potentiometers 64, and 65, until no resultant current flows in circuit 60, 61.

In series with circuit 60, 61 are leads 62, 63 connecting to an amplifier A_4 . The output of amplifier A_4 is led to a glow tube G_2 , before which runs a film 50, a usual light slit being shown between the glow tube and film at 51. This film 50 takes a record 52 of the amplifier distortion representing current.

In Fig. 2 is shown the film 14 with the original sound record N_0 having a variable outline 32, the record being shown greatly enlarged for the purpose of exhibiting more clearly the relations between the several records utilized in the system. Fig. 3 shows the original electrical current wave 30' in circuit 12, 13, which current was used in making original record N_0 . Fig. 4 shows the distorted current wave 31 in circuit 20, 21, wave 31 being like wave 30' except for the distortions of glow tube G_1 , reproducing system P_1, A_2, H and system M_2, A_3 , which last matches system M_1, A_1 . It will be understood that while the current wave 31 is obtained directly from the sound current in circuit 12, 13, current wave 31 is the same, in effect, as would be obtained by reproduction of record N_0 . Distorted current wave 31 is shown superposed in dotted lines upon original current wave 30' in Fig. 3, and it will be observed that the distortion introduced by the system is represented by the difference between curves 30' and 31. Whether the amplitude of the distorted wave 31 is greater or less than that of original wave 30' depends upon the resultant total of the individual characteristics of the several units involved, and in any specific case may depend upon the varying factors of sound character, such for instance as sound frequency. In other words, the amplitude distortion may be either plus or minus with respect to the original current, and although only the plus case is here illustrated it will become apparent that the system corrects the distortions in either case.

Fig. 5 shows the distortion representing current wave 34 obtained when the currents of circuits 12, 13 and 20, 21 (Figs. 3 and 4) are differentially combined in circuit 60, 61, this resultant current wave representing the difference of said currents when oppositely combined. Thus, with the system in balance, the current in circuit 60, 61, may be an alternating current representing the difference of the currents in circuits 12, 13 and 20, 21, the direct current sound representing components being entirely neutralized, while the output of amplifier A_4 consists of a direct current with an amplification of the distortion representing current wave 34 impressed upon it.

Fig. 6 shows the film 50 having a distortion representing record C , made by recording the current output wave of amplifier A_4 , said record having a variable outline 52 which represents the differential or distortion current wave 34 in circuit 60, 61 and in the output circuit of amplifier A_2 .

It will be understood that whether a peak or

a depression in the final output current wave of amplifier A₄, and correspondingly in the correction record C, results from any particular half-cycle of the distortion representing input current to amplifier A₄, depends upon the polarity of the input with respect to the amplifier. There is here taken for illustration the case in which a peak in the correction record C corresponds to peaks in the original and distortion currents 30' and 31', respectively, (Figs. 3 and 4). A film 53 is then printed along one edge with a positive record C' of the negative correction record C obtained as just described, and with an original negative N₀ along the other, as shown in Fig. 7, care being taken that the two prints, the original record and the correction record, are accurately registered with each other.

In case the polarity of amplifier A₄ is reversed with respect to circuit 60, 61, the positive correction record C' may be obtained directly, and may be printed directly with the original record N₀, as in Fig. 8. The system shown in Fig. 8 is generally similar to that shown in Fig. 1, but may be considered as having its input leads to amplifier A₄ reversed from the arrangement of Fig. 1, so that the correction record obtained will be positive C' rather than the negative C. In the case illustrated, the correction record C' is made directly upon the film 14 which takes the original negative N₀, so that the final film illustrated in Fig. 7 is obtained in one step.

In either case, whether the record of Fig. 7 has been made by the system of Fig. 1 and subsequent printing operations, or directly by the system of Fig. 8, there has then been added to the original record N₀ a correction band of opacity C' which varies in width by the amount of the distortions and in a direction or sense negative to that of the distortions. Another manner of expressing this relation is that there has been added to the original record a compensating band of opacity which varies by the amount of but reversely to the distortions of the system.

The result of running the distortion corrected film 53 through the reproducing system is then that the distortions associated with the reproducing system act to correct the sound waves of this oppositely distorted record by exact neutralization of the compensating additions, thereby bringing the wave back to its original shape and proportions, and thus the original audible sound is finally reproduced with the reproduction distortions cancelled.

The system has thus far been described as compensating solely for the disabilities of reproduction; but the system actually compensates for the relatively small disabilities of recording as well, as will now be explained. Starting at the microphone M₁ in Fig. 1, the sound wave representation, after passing through amplifier A₁ and being transformed from a modulated electric current to modulated light waves, has become distorted by the elements of the recording system, and the original sound record N₀ therefore contains those recording distortions. The sound current picked up by the photoelectric cell P₁, which current also has those recording distortions, is passed through the amplifier A₂, and, with the additional distortions of reproduction, is reproduced as sound. The distorted sound is then picked up by microphone M₂ and the resulting current passed through amplifier A₃ therefore contains the distortions of original recording, plus the distortions of reproduction, plus the distortions of microphone M₂ and amplifier A₃, which

last correspond to the recording distortions of M₁ and A₁ and hence may be referred to as recording distortions. It will be observed that the recording distortions are added twice. The current in circuit 12, 13, it will be remembered, contains the distortions of the original recording elements M₁ and A₁, so that the current obtained by differentially combining the output of amplifier A₃ with the current in circuit 12, 13, is then the difference of said two currents, and comprises only the distortions of recording plus the distortions of reproduction. The record C is therefore a record of the distortions of recording plus the distortions of reproduction. The original record N₀, which contains the distortions of recording, is then compensated by the addition of correction band C' both for its distortions of recording and also for the distortions of its reproduction. Both the recording and reproducing systems utilized to modify the records must, of course, be the same, or have identical characteristics, as the ones used originally in recording and in finally reproducing the sound.

The system as now described is capable of considerable modification and rearrangement by varying printing operations, and by substituting positives for negatives, and vice versa, in various parts of the system; and the electrical system is also capable of considerable modification, all within the scope of the invention. Therefore I wish it to be understood that the invention is not to be limited except as may be construed by a fair interpretation of the appended claims.

I claim:

1. The method of correcting sound records that includes, producing an electrical sound current from the original sound, simultaneously making an original sound record from the sound current, and audibly reproducing sound from the sound current, such sound having the distortions of reproduction, producing an electrical sound current from the distorted sound, differentially combining said last mentioned sound current with the first mentioned sound current in such a manner that the sound currents are neutralized except for a distortion-representing current, making a correction record of the distortion-representing current, and making a distortion-corrected record by modifying the original record by the correction record in such a manner as to add the distortions reversely to the original record.

2. The method of correcting sound records that includes, producing an electrical sound current from the original sound, simultaneously making an original sound record from the sound current, and audibly reproducing sound from the sound current, such sound having the distortions of reproduction, producing an electrical sound current from the distorted sound, differentially combining said last mentioned sound current with the first mentioned sound current in such a manner that the sound currents are neutralized except for a distortion-representing current, and placing a record of the distortion-representing current in such association with the original record as to add the distortions reversely to the original record.

3. The method of correcting sound records that includes producing an electrical sound current from the original sound, simultaneously making an original photographic sound record from the sound current, and audibly reproducing sound from the sound current, such sound having the distortions of reproduction, producing an electrical sound current from the distorted sound, differentially combining said last mentioned sound cur-

- rent with the first mentioned in such a manner that the currents are neutralized except for a distortion-representing current, making a photographic correction record of the distortion-representing current, and making a photographic distortion-corrected record by modifying the original record by the correction record in such a manner as to distort said original record reversely to the distortions introduced in reproduction.
- 10 4. The method of correcting sound records that includes, producing a sound current from the original sound, simultaneously making an original photographic sound record from the sound current, and audibly reproducing sound from the sound current, such sound having the distortions of reproduction, producing a distorted sound current from the distorted sound, differentially combining said distorted sound current with a sound current representing the original sound, in such a manner that the sound currents are neutralized except for a distortion-representing current, making a photographic distortion-corrected record by printing a film with an original record and with a positive of the correction record, all in such a manner that the distortions are added reversely to the original record.
- 15 5. The method of correcting sound records that includes, producing an original sound current from the original sound, making an original photographic sound record from the original sound current, audibly reproducing sound corresponding to the said original sound current, such sound having the distortions of reproduction, producing a distorted sound current from the distorted sound, differentially combining said distorted sound current with a portion of the original sound current in such a manner that said currents are neutralized except for a distortion-representing current, making a photographic correction record negative of the distortion-representing current, and making a photographic distortion-corrected record by printing a film with an original record and with a positive of the correction record, all in such a manner that the distortions are added reversely to the original record.
- 20 6. The method of correcting sound records that includes, producing an original sound current from the original sound, making an original photographic sound record from the original sound current, audibly reproducing sound corresponding to said original sound current, such sound having the distortions of reproduction, producing a distorted sound current from the distorted sound, differentially combining the distorted sound current so produced with a portion of the original sound current undistorted by reproduction, in such manner as to obtain a resultant distortion representing sound current, and photographic recording means for recording said distortion representing current.

rents are neutralized except for a distortion-representing current, making a photographic correction record of the distortion-representing current and modifying said original record by the correction record in such a manner as to add the distortions reversely to the original record.

5 7. The method of correcting sound records that includes, producing an original sound current from the original sound, making an original sound record from said sound current, audibly reproducing sound from said sound current, such sound having distortions of reproduction, producing a distorted sound current from the distorted sound, differentially combining said distorted sound current with a sound current representing the original sound, in such a manner that the sound currents are neutralized except for a distortion-representing current, making a correction record of said distortion-representing current, and making a distortion corrected record by modifying the original record by the correction record in such a manner as to add the distortions reversely to said original record.

10 8. The method of correcting sound records that includes, producing an original sound current from the original sound, making an original sound record from said sound current, audibly reproducing sound from said sound current, such sound having distortions of reproduction, producing a distorted sound current from the distorted sound, differentially combining said distorted sound current with a portion of the sound current used in making said original record, in such a manner that the sound currents are neutralized except for a distortion-representing current, making a correction record of the distortion-representing current, and making a distortion corrected record by modifying the original record by the correction record in such a manner as to add the distortions reversely to said original record.

15 9. In a system for correcting sound records, means for producing an original electrical sound current from the original sound, photographic sound current recording means actuated by said original sound current, means for reproducing sound with the distortions of reproduction from the sound current, means for producing a distorted electrical sound current from the distorted sound, means for differentially combining the distorted sound current so produced with a portion of the original sound current undistorted by reproduction, in such manner as to obtain a resultant distortion representing sound current, and photographic recording means for recording said distortion representing current.

40 ROY J. POMEROY.
